SPARK PLUG

Edward B. Nowosielski, Bloomfield, N. J., assignor
to Eclipse Aviation Corporation, East Orange,
N. J., a corporation of New Jersey

Original application May 1, 1930, Serial No.
449,039. Divided and this application November
5, 1934, Serial No. 751,601

8 Claims. (Cl. 123—169)

This invention relates to ignition systems for internal combustion engines and more particularly to spark plugs.

One of the objects of the present invention is to provide an improved spark plug which is both mechanically and electrically strong, and is capable of long service without mechanical or electrical faults.

Another object is to provide an improved spark plug which embodies novel means for preventing the escape of gases from the engine cylinder through the spark plug structure with a consequent loss of compression.

A further object is to provide a spark plug embodying a novel gas-tight seal and an improved shielding means which on account of its simplicity and small number of parts is rugged in structure, cheap to manufacture and easy to assemble.

Several embodiments of the present invention are illustrated in the accompanying drawing, but it is to be expressly understood that said drawing is for the purpose of illustration only and is not to be construed as a definition of the limits of the invention, reference being had for this purpose to the appended claims.

In the drawing:

Fig. 1 is a side elevation partly in section of one embodiment of the present invention;

Fig. 2 is a side elevation partly in section of a second embodiment of the invention.

Referring now to the drawing, wherein like reference characters indicate like parts throughout the several views, Figs. 1 and 2 illustrate an improved spark plug which embodies novel means for forming a gas-tight seal to prevent the escape of gases through the body of the spark plug from the engine cylinder. In the form shown, said plug comprises, in general, a body portion, a positive electrode and a negative electrode. Body portion 7 is exteriorly threaded as at 8 for threaded engagement with an opening in a cylinder wall of an internal combustion engine in the usual manner. The upper part of body portion 7 is internally threaded as at 9 and is of larger diameter than the lower part so as to provide an inner shoulder 10.

The positive electrode comprises a metallic spindle 11 having at its lower end an enlarged head 12, which carries a spark gap joint 13. An insulator 14, preferably a mica sleeve, surrounds electrode 11 practically throughout its length, resting at its lower end on head 12. A plurality of insulating washers 15, preferably of mica, surround the lower portion of electrode 11 and in-

sulating sleeve 14 adjacent head 12, said washers also resting upon head 12 and preferably being of increasing outer diameter away from said head. On top of insulating washers 15 there is seated a gland 16 externally threaded as at 17, and surrounding the intermediate portion of electrode 11 and insulating sleeve 14, but separated therefrom so as to provide a space for the insertion of packing material. Gland 16 is provided with an inclined bottom portion 18, the outer surface of which conforms in slope to shoulder 10 of body portion 7, and with an annular groove 19 formed in its inner surface for purposes later to be described.

In the space thus formed between insulating sleeve 14 and gland 16, there is provided a sleeve 20 of compressible packing material, preferably copper. This sleeve 20 of compressible material is forced between insulating sleeve 14 and gland 16 under great pressure by any suitable means so that groove 19 of gland 16 is completely filled with said material, and insulating sleeve 14 is wedged into close engagement with electrode 11 thus forming a double gas-tight seal around the electrode.

A plurality of other insulating washers 21 are provided resting on top of gland 16 and surrounding substantially the remaining upper portion of electrode 11 and insulating sleeve 14, said washers preferably decreasing in diameter toward the top of electrode 11. Retaining head 22 is then placed around the top of electrode 11 and rests upon washers 21. Retaining head 22 is provided with a counter-sunk bore 23 into which the top of electrode 11 is expanded by upsetting, or any other suitable method, thus tightly clamping together on said electrode, between retaining heads 22 and bottom head 12, the assembly comprising washers 21, gland 16, sleeve 20, and washers 15.

Suitable means are provided for attaching a cable or lead to electrode 11 which, in the form shown, comprise a terminal member 24 constructed with a split spring tip or terminal post 25. Terminal member 24 is placed over and in contact with electrode 11 and retaining head 22, and is secured thereto by a spun-over flange 26 which engages a corresponding collar 27 formed on retaining head 22.

The negative electrode of the spark plug preferably comprises a substantially cup-shaped metallic thimble 28 having in its bottom a plurality of perforations 29 through one of which extends point 13 of the positive electrode 11. Electrode 28 has its rim bent outwardly so as to form a flange 30 for the purpose of engaging shoulder 55

10 formed in body portion 7, when the spark plug is assembled.

In assembling the spark plug, the negative electrode 28 is placed in body portion 7, flange 5 30 resting on shoulder 10. The positive electrode assembly as described above, is then threaded into body portion 7, the inclined bottom portion 18 of gland 16 tightly clamping flange 30 of electrode 28 between it and shoulder 10 to form 10 a gas-tight joint at this point. If desired, flange 30 may be doubled upon itself so as to afford an extra thickness of metal at this point, thereby insuring the gas-tight integrity of the joint, and rendering it unnecessary to employ the usual 15 gasket.

15 A lead or wire 31 is connected to the terminal post 25 in any suitable manner, and, as shown, is provided with a terminal ring 32 which is adapted to slip over the split terminal 25. Lead 20 31 is covered with suitable insulation 33, and when the plug is shielded in the manner illustrated and claimed in my co-pending application Serial No. 449,039 (of which application the present case is a division) the insulation is in turn 25 covered by a metallic sheathing of woven wire, or other suitable material, having contact with the shield portion of the plug.

In Fig. 2 there is illustrated another embodiment of the present invention. In this form, the 30 packing material placed between the insulating sleeve 14 and gland 16 comprises a pair of wedge rings 48 and 49 of compressible material such as copper. These rings are placed between sleeve 14 and gland 16 with their inclined faces in 35 engagement with the base of ring 48 resting on the inclined bottom portion 18 of gland 16. Pressure is then applied, by any suitable means, to the top of ring 49, and the resultant expansion of the rings form a double gas-tight seal 40 around electrode 11 in a similar manner as described for sleeve 20.

There is thus provided an improved spark plug structure which is rugged and strong both mechanically and electrically, and which is compactly and easily assembled from a small number 45 of parts. Due to its simplicity, it is also cheap to manufacture. Novel means are provided in this spark plug for effectively preventing the escape of gases from the engine cylinder, through 50 the spark plug structure, and thus decreasing the loss of compression, as well as prolonging the life of the plug.

It will be obvious that the invention is not 55 limited to the specific forms described and illustrated in the drawing, but is capable of a variety of mechanical embodiments. Various changes, which will now appear to those skilled in the art, may be made in the form, details of construction, and arrangement of parts without departing from the spirit of the invention. Reference is therefore to be had to the appended claims for a definition of the limits of the invention.

This application is a division of my co-pending 65 application, Serial No. 449,039, filed May 1, 1930.

What is claimed is:

1. In a spark plug, the combination of a hollow body interiorly threaded at its upper end, and having an internal shoulder therein, an insulated electrode positioned within said body, a cupped electrode within said body and having a flange engaging said shoulder, a gland threaded into said body and having an inclined bottom portion in engagement with said flange, said 70 gland surrounding said insulated electrode but 75

separated therefrom, an annular groove formed in the interior surface of said gland, and a sleeve of compressible material interposed between said gland and said insulated electrode and resting at its lower end on said inclined bottom portion, said sleeve being forcibly compressed within said gland so as to fill said annular groove, thus forming a gas-tight seal between said electrode and said gland. 5

2. In a spark plug, a body having an internally threaded bore, a thimble forming an electrode removably mounted in said body, a gland threaded into said body and having an inclined bottom portion, an annular groove formed in the inner surface of said gland, a center electrode 10 operatively associated with the thimble electrode and extending through and separated from said gland, compressible insulation surrounding a portion of said center electrode, a plurality of mica discs interposed between a shoulder on the center 15 electrode and the inclined bottom portion of said gland, a sleeve of compressible material interposed between said compressible insulation and said gland, and resting at its lower end on said inclined bottom portion, said sleeve being forcibly compressed within said gland so as to fill said annular groove and compress said insulation making a gas-tight seal between said center electrode and said gland, a plurality of mica washers 20 surrounding said center electrode and insulation and resting on the upper surface of said gland, and cable connecting means secured to the upper end of the center electrode and having engagement with the upper one of the last 25 mentioned washers. 30

3. In a spark plug, the combination of a hollow body interiorly threaded at its upper end, an insulated electrode extending through said body, a gland surrounding said insulated electrode but separated therefrom, said gland being threaded 40 into said body and provided with an annular groove formed in its inner surface, and compressible packing means interposed between said gland and said insulated electrode, said means comprising a soft metal sleeve which is forcibly compressed with said gland so as to fill said annular groove, thus forming a gas-tight seal between said electrode and said gland. 45

4. In a spark plug having a body portion, an assembly adapted to be inserted in said body portion as a unit comprising a center electrode having a head on the lower end thereof, insulation surrounding the electrode above said head, a cup-shaped electrode surrounding the lower end of said first named electrode and having an outwardly flared rim engaging a shoulder formed on the inner surface of said body portion, a compressible member surrounding said first named electrode, and means for forcing said compressible member into engagement with the insulation around said electrode and at the same time firmly seating the outwardly flared portion of said cup-shaped electrode on said shoulder, said last named means including a gland threadedly engaging the body portion of the plug and also engaging said compressible member. 50

5. In a spark plug, a hollow body having an internal shoulder therein, an insulated electrode extending through said body, a cup-shaped electrode within said body and having a flange engaging said shoulder, and means surrounding said insulated electrode and including a gland carried by said body for maintaining said flange in sealing engagement with said shoulder. 70

6. In a spark plug, a body portion, an insulated center electrode therein, a grounded electrode carried by the body portion, and metallic means engaging a portion of said grounded electrode for maintaining both of the electrodes in operative position in said body portion.
7. In a spark plug, a body portion, an insulated center electrode in said body portion, a grounded electrode, and means for retaining said center electrode in said body portion, said means having engagement with a portion of said grounded electrode to form a gas-tight seal between the body, grounded electrode and means.
8. In a spark plug, a hollow body having an internal shoulder therein, an insulated electrode extending through said body, a second electrode having a flange engaging said shoulder, and means surrounding said insulated electrode and including a gland carried by said body for maintaining said flange in sealing engagement with said shoulder.

10

EDWARD B. NOWOSIELSKI.
